SPEED REGULATING DEVICE FOR PRIME MOVERS

Filed July 14, 1927,

UNITED STATES PATENT OFFICE

ALBERT LÜTHI, OF ZURICH, SWITZERLAND, ASSIGNOR TO THE FIRM AKTIENGESELLSCHAFT DER MASCHINENFABRIKEN ESCHER WYSS & CIE., OF ZURICH, SWITZERLAND

SPEED-REGULATING DEVICE FOR PRIME MOVERS

Application filed July 14, 1927, Serial No. 205,729, and in Switzerland July 17, 1926.

Speed regulating devices, or governors, for prime movers are already known in which two gear pumps are used for supplying auxiliary fluid pressure media. Such a device is 5 illustrated in Fig. 1 of the accompanying drawings, in which figure the numeral 1 designates one of these two pumps. This pump 1 is driven by the prime mover designed as a steam turbine 30 the rotary speed of which it is desired to regulate through a worm-gearing 31, and consequently said pump partakes of the speed fluctuations of the machine 30. The pump 1 which is connected to a reservoir 33 containing a liquid forces liquid under 10 pressure through a diaphragm 2, in front of which the speed fluctuations of the pump 1 manifest themselves in the form of fluctuations of pressure. These pressure fluctuations act upon a plunger 4 which is under 15 the influence of a tension spring 5 and to which is also secured a fluid tight diaphragm 6. The second pump is indicated in Figure 1 of the drawings by the numeral 7; it is driven by the steam turbine 30 through a worm-gearing 20 32 and supplies liquid under pressure from the reservoir 33 to a pressure chamber 8. This latter is provided with a vent or nozzle opening 9 which is so controlled by the plunger 4 that when the pressure rises in 25 front of the diaphragm 2, that is to say, when the pressure in receiving-chamber 10 increases, the auxiliary liquid delivered by the pump 7 can escape more readily through the 30 said opening 9, so that the pressure in the chamber 8 falls when the rotary speed of the prime mover to be governed increases. The pressure chamber 8 is in permanent connection with a space 12 above a piston 11 contained in a cylinder 11' and upon the under- 35 side of which piston acts, a constant pressure prevailing behind diaphragm 2 in the discharging chamber 21, which is either open to atmospheric pressure or connected to the lubricating system of the prime mover, and 40 also a spring 13. The lower space of the cylinder 11' discharges into the chamber 21. The piston 11 is operatively connected to the speed regulating member proper 34 (e. g. an inlet valve) of the turbine 30 the speed of 45 which is to be governed.

If the speed of the turbine 30 drops by reason of increased load, the pumps 7 and 1 discharge less liquid to their chambers 8 and 10.

If first the operation of pump 7 be considered, the pressure in chamber 8 will decrease and the pressure on the upper surface of the piston 4 will be reduced and the spring 5 will lift the piston 4 until the pressure in chamber 8 is substantially the same as it was before the reduction of speed of the turbine. 55

Pump 1 also reduces the pressure in chamber 10 so that the spring 5, by reason of the reduction of pressure on piston 4, will draw the piston still further to the opening in nozzle 9. 60

The pressure in chamber 8 consequently becomes greater than before the speed reduction of the turbine 30. The increased pressure in chamber 8 now acts through chamber 12 on piston 11 against the action of spring 13, the piston 11 moves down, and with it the steam inlet valve 34 to admit more steam to the turbine. 70

A screw 14 which enables the tension of the spring 5 to be increased or decreased provides for adjustment of the number of revolutions per minute to the desired value. 75

It is the object of the present invention, in a speed governing device of the kind above described, to eliminate one of the two pumps 80 which supply auxiliary pressure fluid. To this end, according to the invention, a part of the pressure fluid which is delivered by the pump which rotates at a speed proportional to that of the machine to be governed flows 85 through an auxiliary throttle device to the pressure chamber the fluid pressure in which determines the setting of the regulating member proper of the machine. 90

Constructions of governor devices in accordance with the present invention are illustrated somewhat diagrammatically and by way of example in the accompanying drawings, in which:

Fig. 2 shows one constructional form of 95 governor device according to the invention.

Fig. 3 is a graphic representation of the manner in which the embodiment shown in Fig. 2 operates.

Fig. 4 shows a second embodiment and

100

105

Fig. 5 a third embodiment of the invention.

The device illustrated in Fig. 2 is differentiated from that shown in Fig. 1 by the fact that it includes no pump such as the pump 7 and, further, by the fact that the receiving chamber 10, which is fed by the pump 1 driven by the machine 30 to be governed, is connected to the pressure chamber 8 by a duct 15 in which is fitted a diaphragm 16 serving as an auxiliary throttling device. In other respects the device is made exactly the same as the known speed governing device above described.

The graphs in Figure 3 show on a rectangular system of co-ordinates the relation between the pressure p_1 in receiving chamber 10 and the pressure p_2 in chamber 8, in a function of the number n of revolutions per minute of the prime mover to be governed.

At low values of n the plunger 4 first closes the nozzle opening 9 and then p_1 and p_2 increase equally, so that $p_1 = p_2$. This condition is shown in curve *a* and it persists until the pressures p_1 and p_2 , acting on the plunger 4, overcome the spring 5, as at the point P in Fig. 3. Pressure fluid then flows not only through the diaphragm 2 but also through the nozzle opening 9. Rise of the pressure p_1 is thus slowed down, as is apparent from curve *b* of Fig. 3 and the pressure p_2 , upon increase of the number n of revolutions per minute, falls off from the point P as indicated by curve *c*. The points P_1 and P_2 of the curve *c* correspond to the pressures p_2 which prevail in the lowest and in the highest positions of the piston 11 respectively. From the projections P_1' and P_2' on to the n -axis of the system of co-ordinates the speed fluctuations of the governed machine between no load and full load can be ascertained. Given the distances of the points P_1 and P_2 from the n -axis, the constant cyclic irregularity becomes greater the flatter the curve *c* runs. Moreover, if the point P be given, the relation of the diaphragm 2 to the diaphragm 16 determines the steepness of the curve *c*. A very steep curve is obtained if the diaphragm 16 be small in relation to the diaphragm 2.

Another way of increasing the steepness of the curve *c* is shown in the construction illustrated in Fig. 4, wherein the plunger 4 is provided with a bore 17 connecting the pressure chamber 8 with another chamber 18 beneath the said plunger. The fluid pressure p_2 prevailing in the chambers 8 and 18 gives an upwardly acting resultant, since that end of the plunger which projects into the chamber 18 presents a surface 18¹ of greater area than that of the opposite end of the plunger which confronts the nozzle 9. A further noteworthy peculiarity of the construction according to Fig. 4 resides in the fact that the diaphragm 2 of Fig. 2 is replaced by an annular gap 20, formed between

a flange or collar 19 on the plunger 4 and the surrounding casing 4¹, the diaphragm 6 of the previous example being thereby rendered superfluous.

Assuming that a pressure p_1 prevails in the receiving chamber 10 and a pressure p_2 in the pressure chamber 8, let Q_1 be the quantity of fluid passing through the gap 20 per second, and let φ_1 and φ_2 be the areas of cross section of the throttling passages 2 and 16, Q_2 being the quantity of fluid passing through the leak hole 16: then φ_1 and φ_2 are so selected that

$$Q_2^2 = \varphi_2^2 \cdot (p_1 - p_2)$$

and

$$Q_1^2 = \varphi_1^2 \cdot (p_1)$$

The pressure in discharging chamber 21 is assumed to be negligibly small. If f_1 be the effective surface of the flange 19 on the plunger 4 upon which the pressure p_1 acts, and if f_2 be the end surface area of the plunger exposed to pressure in the chamber 18, less the surface of the nozzle 9, (i. e. the effective surface subjected to the pressure p_2), it can be proved that for any desired couple of values p_1 , p_2 , the plunger 4 is in stable equilibrium when

$$\frac{f_2}{f_1} < \frac{1}{1 + \frac{\varphi_1}{\varphi_2} \sqrt{1 - \frac{p_2}{p_1}}}$$

Taking into account the most unfavorable case in which $p_2 = 0$, this gives the following practical formula for the formation of the member 4:

$$\frac{f_2}{f_1} < \frac{1}{1 + \frac{\varphi_1}{\varphi_2}}$$

If particularly f_2 be made so extremely small as to be negligible the choice of the ratio $\frac{\varphi_1}{\varphi_2}$ need not be restricted in any way.

It can be proved, that in the construction according to Fig. 4 with the same diaphragm or ratio, the curve *c* may be made to fall off more steeply than in the construction according to Fig. 2.

Fig. 5 illustrates a form of construction wherein, for the purpose of reducing friction, an oscillating lever 4^a is substituted for the plunger 4, the said lever penetrating the partition wall 25 between the receiving chamber 10 and the pressure chamber 8. This lever 4^a carries a plate 23 surrounded by an annular gap 20 and also a small plate 24 adapted to cooperate with a vent or nozzle opening 9; further the said lever is biased by a tension spring 5. The manner in which the device according to Fig. 5 operates is the same as in the case of the device according to Fig. 4. In particular the same conditions for stability obtain.

The devices above described are especially applicable to engines used for driving rotary compressors.

I claim:

- 5 1. A device for governing the speed of prime movers provided with a regulating member; comprising a liquid pump constantly driven by the machine to be governed, a receiving chamber into which said pump 10 constantly delivers a quantity of pressure liquid varying in dependence of the speed of said machine, a piston connected with said regulating member, a cylinder containing said piston, a discharging chamber into which liquid from said cylinder discharges, a pressure chamber from which liquid is supplied to said piston and having a vent therefrom, means of constant area to throttle the flow from said receiving chamber to said pressure chamber, means to control the venting 15 of liquid from the pressure chamber, and means to throttle liquid by-passing the pressure chamber and liquid flowing from the receiving chamber into the discharging chamber, the means to control the venting of liquid from the pressure chamber being moved by the differential liquid pressure between the receiving chamber and the discharging chamber.
- 20 2. A device for governing the speed of prime movers provided with a regulating member; comprising a liquid pump constantly driven by the machine to be governed, a receiving chamber into which said pump 25 constantly delivers a quantity of pressure liquid varying in dependence of the speed of said machine, a piston by which the regulating member is moved, a cylinder containing said piston, a discharging chamber into which liquid from said cylinder discharges, a pressure chamber from which liquid is supplied to said cylinder above the piston and having a vent therefrom, a diaphragm having a constant area opening for 30 throttling the liquid passing from the receiving chamber to the pressure chamber, a valve to control said vent, and means to throttle liquid by-passing the pressure chamber and liquid flowing from the receiving chamber, the means to control said vent being moved by the differential liquid pressure between the receiving chamber and the discharging chamber.
- 35 3. A device for governing the speed of prime movers provided with a speed regulating member; comprising a pump which partakes in the speed fluctuations of the machine to be governed and constantly delivers a quantity of pressure liquid varying in 40 dependence on the speed of the machine, a throttling device through which is forced a part of the pressure fluid delivered by said pump, a movable member acted upon by the pressure prevailing in front of said throttling device, a pressure chamber provided

with a nozzle confronting one end of said movable member, means formed integral with said movable member to throttle liquid by-passing the pressure chamber, and means adapted to act on the speed regulating member of the prime mover in dependency of the liquid pressure prevailing in said pressure chamber, said movable member being provided with a bore extending from one of its ends to the opposite end, the surface area of the end confronting the nozzle of the pressure chamber being smaller than the surface area of its other end, so that the liquid pressure acting on said two ends of the movable member gives a resultant force moving said member in a direction such as to tend to close said nozzle.

4. A device for governing the speed of prime movers provided with a speed regulating member; comprising a pump which partakes in the speed fluctuations of the machine to be governed and constantly delivers a quantity of pressure liquid varying in dependence on the speed of the machine, a throttling device through which is forced a part of the pressure fluid delivered by said pump, a movable member acted upon by the pressure prevailing in front of said throttling device, a casing enclosing said movable member, a flange on the movable member forming together with a part of said casing a gap which functions as a throttling device for a part of the pressure fluid delivered by said pump, a pressure chamber provided with a nozzle confronting one end of said movable member, and means adapted to act on the speed regulating member of the prime mover in dependency of the liquid pressure prevailing in said pressure chamber, said movable member being provided with a bore extending from one of its ends to the opposite end and the surface area of the end confronting the nozzle of the pressure chamber being smaller than the surface area of its other end, so that the liquid pressure acting on said two ends of the movable member gives a resultant force moving said member in a direction such as to tend to close said nozzle.

In testimony whereof, I have signed my name to this specification.

ALBERT LÜTHI.
